N. Y., A CORPORATION OF NEW YORK.

WEB-PRINTING MACHINE.

1,155,619.

Specification of Letters Patent.

Patented Oct. 5, 1915.

Application filed November 20, 1914. Serial No. 873,079.

To all whom it may concern:

Be it known that I, OSCAR ROESEN, a citizen of the United States, residing at New York, county of New York and State of New York, have invented certain new and useful Improvements in Web-Printing Machines, fully described and represented in the following specification and the accompanying drawings, forming a part of the same.

10 This invention relates to certain improvements in web printing machines.

In web printing machines, it is usual to print and perfect one impression on each side of two webs, the two perfected webs being then, if desired, further manipulated in different ways to produce various products. It is also frequently desirable in web printing to print and perfect one web having two impressions on each side, this being particularly desirable in color printing.

20 To obtain the best results when one web is to be given two impressions on one side and perfected, it is desirable, to effect proper registry and for other reasons, that the two impressions be made as close together as possible. The usual arrangement adopted for this is to employ two sets of printing mechanisms, one for printing each side of the web, so as to perfect the latter, each printing mechanism

25 employing two plate cylinders and an impression cylinder, the impression cylinder being located between the plate cylinders, so that a very short interval shall elapse between the two impressions on the same side of the web. With a machine constructed to effect this, however, it is not possible to print one impression on each side of two webs. To make it possible to print and perfect two webs with one impression on each side, and

30 one perfected web with two impressions on each side, a machine has been provided employing four separate printing couples, each including a form member and an impression member. When one impression is to be made on one side of two webs, two of these couples

35 were utilized for printing and perfecting one web, and the other two for printing and perfecting the other web. When, however, in this machine, one web was to be printed with

40 two impressions on one side and perfected, the web had to be led through all four of the couples and since necessarily these couples were spaced apart, a considerable interval elapsed between the first and second im-

pressions on the same side of the web, with 55 consequent tendency to non-register. This arrangement, furthermore, had other disadvantages.

It is the object of the present invention to produce a web printing machine in which 60 the printing elements are so arranged that two webs can be printed and perfected with one impression on one side, and at the same time one web can be printed and perfected with two impressions on the same side, with 65 a very small interval between the two impressions, so that accurate registry is secured.

A further object of the invention is to produce a printing mechanism for effecting 70 these results which shall be simple and compact.

A mechanism for carrying out the invention is diagrammatically illustrated in the drawings, in which—

75 Figure 1 is a diagrammatic side elevation of so much of a press as is necessary for an understanding of the invention; the press in the construction shown in this figure being arranged to print and perfect two webs with 80 one impression on each side; and Fig. 2 is a view similar to Fig. 1, the press being shown as printing and perfecting two impressions on the same side of one web.

Referring now to the drawings, the particular machine which has been selected to illustrate the invention is a rotary machine, in which the form and impression members are cylinders, although, if desired, the invention may be employed in machines in which 90 all the printing elements may not be cylinders.

Referring first to the construction illustrated in Fig. 2, there are indicated two sets of printing mechanisms A, B, which are or 95 may be duplicates of each other. Each of these sets in the particular construction illustrated includes form cylinders 1, 2, these cylinders being preferably arranged substantially vertically of each other. The 100 ink is supplied to these form cylinders from ink reservoirs 3, 4 through the usual train of ink distributing rolls 5, 6. Coöperating with the form cylinders, is an impression cylinder 7, the form cylinders being arranged so as to have quick successive printing relation with this cylinder 7, being 105 mounted to effect this in the particular con-

struction illustrated on the same side of the axis of cylinder 7. Two form cylinders and the impression cylinder are furthermore arranged so that their printing relations 5 may be changed, so that in one position the form cylinders are both in printing relation with the impression cylinder, and, in another position, one only of the form cylinders is in printing relation with the impression cylinder. This change of the printing 10 relation of these cylinders may be effected in various ways, but in the particular construction illustrated the impression cylinder 7 and form cylinder 2 are arranged so that 15 they may be thrown into and out of printing relation with each other. In the best constructions, and as illustrated, the impression cylinder 7 will be mounted so that it can be moved or tripped out of printing 20 relation with the form cylinder 2, continuing, however, in printing relation with form cylinder 1. Any suitable mechanism may be employed for thus moving or tripping the cylinder and, as many such mechanisms are 25 known in the art, which may be employed, none has been illustrated because unnecessary for an understanding of the invention. The second set of printing mechanism which 30 may be used is indicated by the letter B and includes two form members illustrated as cylinders 9, 10 inked from suitable ink reservoirs 11, 12, through the usual chain of distributing rolls 13, 14. Coöperating with form cylinders 9, 10, which, as shown, are 35 arranged preferably substantially vertically of each other, is an impression cylinder 15. Like the cylinders in set A, the form cylinders 9, 10 are arranged so as to have quick successive printing relation with impression cylinder 15, being mounted for this purpose preferably as shown on the same side of the axis of the impression cylinder. These form cylinders and impression cylinders, furthermore, are arranged so that their 40 printing relation may be changed, the cylinders being mounted so that the impression cylinder may, in one position, be in printing relation with both form cylinders, and, in another position, be in printing relation 45 with but one of the form cylinders. While this change in the printing relation of the cylinders may be effected in various ways, preferably impression cylinder 15 will be mounted so that it can be moved or tripped 50 out of printing relation with one of the form cylinders, it being tripped out of printing relation in the particular construction illustrated with form cylinder 9 through suitable tripping mechanism, not 55 illustrated, the position of the cylinder, when so moved, being indicated in the drawings by dotted lines. In accordance with the invention, and for purposes which will hereinafter appear, two other impression cylinders 16, 17 are provided which may,

through suitable tripping mechanism, not shown, be brought into and out of printing relation with the form cylinders 2, 9.

In the construction illustrated in Fig. 2, the web W is to be printed with two impressions on one side, as, for instance, in two colors and perfected. When this is to be done, the cylinders 16, 17 occupy the position shown in full lines in Fig. 2, that is, they have been tripped out of printing relation with the form cylinders 2, 9, the cylinders 7, 15 having been tripped into the position shown in full lines in the figure, so that the cylinder 7 is in printing relation with the form cylinders 1, 2, and the cylinder 15 is in printing relation with the form cylinders 9, 10. The web W is led from the web-roll through the usual draw-off rolls 18 around guide-rolls 19 between the form cylinder 1 and the impression cylinder 7, where it is given its first impression. It then continues between impression cylinder 7 and form cylinder 2, where it is given its second impression on the same side. As will be seen with the arrangement adopted, the two form cylinders are so arranged that the two impressions are made on the web at a very short interval and thus there is effected accurate registry of the two impressions. After the two impressions have been given on one side in mechanism A, the web is perfected in mechanism B, being conducted thereto over a guide-roll 20 between cylinders 10, 15, where the first impression is given, and then between cylinders 15, 9, where the second impression is given, the arrangement of these cylinders being the same as in mechanism A, so that a very short interval elapses between impression. If desired, an offset web 21 may be provided passing over a guide-roll 22 and meeting the printed web at guide-roll 20, the offset member being rewound on a rewinding-roll 22. After the web has been given its second or perfected impression, it may be led over guide-rolls 23, 23, to a cutting and folding mechanism, or may be otherwise manipulated as desired.

With the construction thus far described, it will be seen that the web is printed and perfected with two impressions on one side, these impressions being so produced as to allow of accurate registry.

When it is desired to print and perfect two webs with one impression on each side, the machine illustrated in Fig. 2 is adjusted so that the parts are in the position shown in Fig. 1. In this arrangement the impression cylinders 16, 17, are tripped so as to be in printing relation with the cylinders 2, 9, and the cylinders 7, 15, are tripped out of printing relation with the cylinders 2, 9, but continue in printing relation with cylinders 1, 10. With this arrangement of parts and simple adjustment of the impression cylin-

ders, two webs can be printed and perfected with one impression on each side, as follows: Web W' is led from a suitable web-roll between the printing and impression cylinders 2, 16, where it is printed on one side, through a printing couple 9, 17, where it is perfected, and over guide-rolls 23 out of the machine. Web W^2 is led from a suitable web-roll through impression cylinders 1, 7, and to and through cylinders 15, 10, where it is perfected, and out of the machine, and may be led with web W' , if desired, to any mechanism for further manipulation.

The cylinders of each set may be driven in any suitable manner. In the particular construction illustrated, the cylinders of mechanism A, and the cylinders of mechanism B are driven from cylinders 1 and 10. When, as shown, cylinders 1 and 10 are driving cylinders, reversing mechanisms, as pinions 24, shown in dotted lines are provided, which reverses the direction of rotation of cylinders 2 and 9. These pinions 24 are mounted so that they may be thrown out of gear with impression cylinder 7 through any suitable construction, not shown, they being so thrown out when the machine is to be used for printing two impressions on the same side of one web, as illustrated in Fig. 2. Certain changes and variations may be made in the specific construction shown and described, without departing from the invention, and the invention furthermore may be employed in machines in which all the printing elements are not cylinders and the invention is not to be restricted to the exact arrangement shown and described.

What is claimed is:

1. In a printing machine, the combination of a set of printing couples including form members and impression members arranged so that two form members may have quick successive printing relation with one impression member, a second set of printing couples including form members and impression members arranged so that two form members may have quick successive printing relation with one impression member, and means for changing the printing relation of the members of each set so that in one position a web may be given multiple impressions on one side in one set and perfected with multiple impressions in the other set, and in another position two webs may each be printed with one impression in one set and perfected in the other.

2. In a printing machine, the combination of a set of rotary printing couples including form cylinders and impression cylinders arranged so that two form cylinders may have quick successive printing relation with one impression cylinder, a second set of

printing couples including form cylinders and impression cylinders arranged so that two form cylinders may have quick successive printing relation with one impression cylinder, and means for changing the printing relation of the cylinders of each set so that in one position a web may be given multiple impressions on one side in one set and perfected with multiple impressions in the other set, and in another position two webs may each be printed with one impression in one set and perfected in the other.

3. In a printing machine, the combination of a set of rotary printing couples including two form cylinders, an impression cylinder, the two form cylinders being located on the same side of the axis of the impression cylinder so as to have quick successive printing relation therewith, a second impression cylinder coöperating with one of the form cylinders, both the impression cylinders being movable relatively to the form cylinders, a second set of rotary printing couples including two form cylinders, an impression cylinder, the two form cylinders of the second set being located on the same side of the axis of the impression cylinder so as to have quick successive printing relation therewith, and a second impression cylinder in the second set coöperating with one of the form cylinders, both impression cylinders of the second set being movable relatively to the form cylinders.

4. In a printing machine, the combination of a set of rotary printing couples including two form cylinders, an impression cylinder, the two form cylinders being located on the same side of the axis of the impression cylinder so as to have quick successive printing relation therewith, a second impression cylinder coöperating with one of the form cylinders, both the impression cylinders being movable relatively to the form cylinders, a second set of rotary printing couples including two form cylinders, an impression cylinder, the two form cylinders of the second set being located on the same side of the axis of the impression cylinder so as to have quick successive printing relation therewith, a second impression cylinder in the second set coöperating with one of the form cylinders, both impression cylinders of the second set being movable relatively to the form cylinders, and guides for directing a web from one set to the other.

In testimony whereof, I have hereunto set my hand, in the presence of two subscribing witnesses.

OSCAR ROESEN.
